UNITED STATES PATENT OFFICE.

JOSEPH L. GOBEILLE, OF CLEVELAND, OHIO, ASSIGNOR TO THE READING STOVE WORKS, ORR, PAINTER & CO., OF READING, PENNSYLVANIA.

DESIGN FOR A COOKING STOVE OR RANGE.

SPECIFICATION forming part of Design No. 31,808, dated November 7, 1899.

Application filed October 11, 1899. Serial No. 733,331. Term of patent 7 years.

To all whom it may concern:

Be it known that I, JOSEPH L. GOBEILLE, a citizen of the United States of America, and a resident of the city of Cleveland, State of Ohio, have invented a certain new and original Design for a Cook Stove or Range, of which the following is a specification.

The drawing is a perspective view of a stove, showing my new design.
10 The leading or material features of my design consist in the form and ornamentation as shown in the drawing, comprising the skirt-base A, of rectangular form, with spiral-curve scrollwork ornamentation a, the rectangular body rising from said base and provided
15 on the front with a rectangular oven-door B,

having a central oval-shaped name-plate and surrounding scrollwork ornamentation corresponding with that upon the skirt-base and an outer oven-shelf c, the fire-box end D of 20 the body overhanging the skirt-base and having front and end fire-doors and hearth. The top E is flat, with overhanging band e.

What I claim is—

The design for a cooking stove or range substantially as shown and described.

Signed by me at Cleveland, Ohio, this 21st day of September, 1899.

JOSEPH L. GOBEILLE.
